WATCHCASE MOUNTING

Edward C. Anderson, Elgin, Ill., assignor to Illinois Watch Case Company, Elgin, Ill., a corporation of Illinois

Application June 19, 1937, Serial No. 149,153

6 Claims. (Cl. 206—37)

This invention relates to a watch case mounting applicable to small cases and receptacles; more particularly the present improvements have to do with a mounting by which the watch case may be shifted from one position to another as required for winding, adjustment or better exposure of the watch.

The features of construction herein disclosed are applicable to cigarette cases, vanity cases, etc., and also to various receptacles having closures, with all of which a watch may be advantageously associated. In the description to follow, as well as in the accompanying drawing, reference is made to a vanity case or compact, but I would have it understood that this is by way of example only.

In the accompanying drawing, Figure 1 is a plan view of a vanity case or compact with which is associated a watch;

Fig. 2 which is a similar view shows the lid only with the watch case removed therefrom;

Fig. 3 is a view of the lid interior with a portion of the bezel broken away to exhibit the mounting frame for the watch case;

Fig. 4 is a transverse section through the lid, taken on line 4—4 of Fig. 3;

Fig. 5 is a view in perspective of the watch case and frame wherein it is mounted; and

Fig. 6 is a fragmentary detail in section on the curved line 6—6 of Fig. 3.

The vanity shown comprises a body B to which is hinged as at 7 a lid L. The case body or receptacle may be adapted for reception within a pocket or pocketbook, or for mounting upon a table or dresser. The lid shown is such as may close over the open face of the body to form a closure therefor. It may, if desired, be equipped with a conventional catch by which to normally remain closed.

Referring particularly to Fig. 4, the lid is shown as somewhat convex with a central aperture 8 therethrough. Along its margins the lid is provided with a shoulder 9 wherewith a bezel 10 is adapted to engage releasably, as by a snap fit. The bezel is formed with a seat 11 for the accommodation of a plate 12 which is desirably a mirror of glass or metal.

The contour of the lid may be variously formed. As illustrated, the lid is provided with certain radial ribs or corrugations 15 (see Fig. 6) with which a frame F in the form of a corrugated ring is adapted to coact. The internal edge of this ring is contoured substantially the same as that of the lid aperture (see Fig. 4), defining therewith a space for the accommodation of a case C in

which is fitted the movement of a watch W. A hinge joint 16 extended from one side of the case is adapted to lie between a pair of complementary hinge joints 17 and 18 which are formed on the frame, permitting a pintle 19 to be extended therethrough to establish a hinged connection between the case and ring.

The watch may be provided with the usual stem having a crown 20 adapted to lie within a recess 21 to one side of the lid aperture, a registering recess 22 being formed in the frame (see Fig. 5). A further recess 23 is provided in the lid aperture to receive the hinge joints which desirably extend therewithin so as to permit free outward swinging movement of the watch case. It is desirable that the joints fit within this latter recess with sufficient accuracy to center the case with respect to the lid aperture, thereby assuring of free in and out movements of the watch case with respect to the lid. When so positioned, the crown will be located within the recess 21 in the manner shown in Fig. 1.

Entirely independent of the coaction between the hinge joints and the lid recess wherein they are accommodated, provision may be made for securing the mounting frame non-rotatively with respect to the lid. In the construction shown, this is accomplished by the radial corrugations of the lid which interfit with those of the frame. Accordingly, so long as the frame is maintained in engagement with the lid in the manner shown in Fig. 6, the frame will remain in a fixed rotative position of adjustment with respect to the lid. Between the bezel supported plate and proximate side of the frame is a space into which the watch case may enter when moved to its closed position. I utilize this space for the accommodation of a resilient ring 25 which is mounted upon a disc 26 having, if desired, an adhesive connection with the back of the plate. This packing ring which serves as a pad bears against the proximate face of the frame to maintain the latter fixedly against the inner face of the lid. By this arrangement a fixed mounting for the watch case is provided, requiring only that the parts be formed and assembled in the manner described. To remove the watch case, should this be desired, it is necessary merely that the bezel be disengaged whereupon the mirror with associated pad may be withdrawn to permit disassembly of the frame, together with its associated watch case, from the lid.

From the foregoing description it will be apparent that the present watch case may be swung down so as to lie in large part within the space

afforded within the confines of the lid. This would be its normal position. For purposes of adjustment, winding, or otherwise, the watch case may be swung outwardly and away from the compartment in the lid wherein it is normally maintained, to occupy a position such as is indicated in Fig. 4. In this latter position the watch case may be left, should it be desired to expose the face of the watch to view from a different angle. These advantages are all inherent in the present construction which is exceedingly simple and involves only certain minor operations in its assembly.

I claim:

- 15 1. In a watch case mounting, the combination of a closure lid having an aperture therethrough, a watch case adapted to enter the aperture to fit freely therewithin, a frame surrounding the aperture and positioned to lie against the inner face of the lid, a hinged connection between the frame and case whereby the latter may swing outwardly from a position within the lid aperture to a point exteriorly thereof, and means for supporting the frame fixedly against the lid.
- 20 2. In a watch case mounting, the combination of a closure lid having an aperture, a watch case fitted loosely within the aperture, a frame surrounding the aperture, a hinged connection between the frame and case, and means detachably securing the frame against the inner face of the lid whereby to provide a fixed mounting for the case adapting it to swing outwardly from the lid aperture.
- 25 3. In a watch case mounting, the combination of a closure lid having an aperture, a bezel fitted to the lid, a mirror mounted in the bezel, a watch case fitted loosely within the lid aperture, a

frame in hinged connection with the case, and means extending between the mirror and frame adapted to sustain the frame in a fixed position against the inner face of the lid and furnish a stop to limit inner swinging movements of the case.

4. In a watch case mounting, the combination of a closure lid having an aperture, a watch case fitted loosely within the lid aperture, a frame within the lid, a hinged connection between the frame and case, the lid aperture being recessed to accommodate the hinged connection whereby the frame is secured against rotation relative to the lid, and means detachably securing the frame against the inner face of the lid whereby to provide a fixed mounting for the case adapting it to swing outwardly from the lid aperture.

5. In a watch case mounting, the combination of a closure lid having an aperture, a watch case fitted to move freely into and out of the lid aperture, a frame having means to engage the lid whereby to secure the one against rotative movement relative to the other, a hinged connection between the frame and case, and means detachably securing the frame against the inner face of the lid whereby to provide a fixed mounting for the case adapting it to swing outwardly from the lid aperture.

6. In a watch case mounting, the combination of a closure lid having an aperture, a watch case adapted to lie within the aperture and move freely in and out thereof, a support fixedly engaging the inner face of the lid adjacent the aperture therethrough, and hinge means located in the plane of the aperture having a connection with the case and with the support.

EDWARD C. ANDERSON.
